THREE BARREL SLIP FIT COUPLING ELEMENT OR THE LIKE

John H. Hosking, Cincinnati, Ohio, assignor to John H. Hosking Co., Cincinnati, Ohio, a corporation of Ohio

Application September 16, 1957, Serial No. 47,744

Term of patent 14 years

(Cl. D54—1).

Fig. 1 is a perspective view of a three barrel slip fit coupling element or the like, showing my new design.

Fig. 2 is a perspective view of the element of Fig. 1 when turned about 180° about the vertical barrel thereof.

Fig. 3 is a rear elevational view of Fig. 1.

The characteristic feature of my design resides in a coupling element having an elongated boss with pointed ends thereon and other bosses of pyramidal configuration.

I claim:

The ornamental design for a three barrel slip fit coupling element or the like, as shown and described.
